CLAIM

The ornamental design for a media streaming device, as shown and described.

DESCRIPTION

1. Media streaming device

1.1: Perspective

1.2: Front

1.3: Back

1.4: Left

1.5: Right

1.6: Top

1.7: Bottom

The present design product is used for collecting, editing or streaming of audio and video data for live webcasting; the essential feature of the present design is the shape; fig. 1.1 best shows the essential features of the present design.

The de-emphasized and half-tone portions shown within the broken lines in reproductions 1.1, 1.2, 1.3 and 1.6 depict portions of the media streaming device which form no part of the claimed design.

1 Claim, 7 Drawing Sheets
